UNITED STATES PATENT OFFICE.

JOHN GILSON, OF PORT WASHINGTON, WISCONSIN.

DESIGN FOR A BRACE-PIECE FOR TABLE-LEGS.

SPECIFICATION forming part of Design No. 32,509, dated April 10, 1900.

Application filed October 20, 1899. Serial No. 734,267. Term of patent 14 years.

To all whom it may concern:

Be it known that I, JOHN GILSON, a citizen of the United States, residing at Port Washington, in the county of Ozaukee and State of Wisconsin, have invented and produced a new and original Design for a Brace-Piece for Table-Legs; and I do hereby declare the following to be a full, clear, and exact description of the same, reference being had to the accompanying drawings, forming a part thereof.

In the said drawings, Figure 1 is a plan view, Fig. 2 a side elevation, and Fig. 3 a detail sectional view, taken on the line 3 3 of Fig. 1, of a brace-piece for table-legs embodying my new design.

My design relates to the new and original shape or configuration of the article.

The leading or essential feature consists in the unitary design for a brace-piece for table-legs made the subject of illustration, comprising the shape of the horizontal top A, with depending outwardly-inclined flanges B B, having parallel-walled perforations C through the outer faces thereof, said flange-faces being formed on the lines of two oblique planes

b c of slightly-different projections, the brace-piece being concavely rounded between the faces of each adjacent flange B, as shown at d d, and the under side of each flange B being formed on rounded convex lines e e, extending upward from the bottom of each flange-face on each side thereof and merging into rounded concave lines f f.

Minor features of said design comprise the shape of the transverse straight upper walls g between the inclined parallel side walls h h of the flange-face openings C and the shape of the straight-edged inwardly-inclined lower walls i of said openings.

Having thus described my invention, what I claim as new, and desire to secure by Letters Patent, is—

The design for a brace-piece for table-legs, substantially as herein shown and described.

In testimony whereof I affix my signature in presence of two witnesses.

JOHN GILSON.
